UNITED STATES PATENT OFFICE

107,109

DESIGN FOR A FALLING WEDGE

John Henry Carter, Bend, Oreg.

Application May 14, 1937, Serial No. 69,361

Term of patent 14 years

To all whom it may concern:

Be it known that I, John Henry Carter, a citizen of the United States, residing at Bend, in the county of Deschutes and State of Oregon, have invented a new, original, and ornamental Design for a Falling Wedge, of which the following is a specification, reference being had to the accompanying drawing, forming part thereof.

Figure 1 is a view in side elevation of a falling wedge, showing my new design.

Figure 2 is an elevational view thereof, taken at right angles to Fig. 1.

The characteristic features of my design reside in a wedge of the configuration shown in the drawing having sharply sloping sides on the head portion and slightly tapering beveled surfaces down the edges thereof, starting from the base of the sloping sides of the head portion and continuing around the cutting edge at the bottom of the wedge.

I claim:

The ornamental design for a falling wedge as shown and described.

JOHN HENRY CARTER.
